UNITED STATES PATENT OFFICE.

WILLIAM HUGH FREELAND, OF DUCKTOWN, TENNESSEE.

FURNACE-CHARGER.

SPECIFICATION forming part of Letters Patent No. 768,596, dated August 30, 1904.

Application filed October 12, 1903. Serial No. 176,756. (No model.)

To all whom it may concern:

Be it known that I, WILLIAM HUGH FREELAND, a citizen of the United States, residing at Ducktown, in the county of Polk and State of Tennessee, have invented certain new and useful Improvements in Furnace-Chargers, of which the following is a full, clear, and exact description, reference being had to the accompanying drawings, forming a part hereof:

10 My invention has relation to improvements in furnace-chargers; and it consists in the novel construction of charging device more fully set forth in the specification and pointed out in the claims.

15 In the drawings, Figure 1 is a side elevation of the carriage and the top of the furnace with movable top or cover, the carriage being disengaged from the cover. Fig. 2 is a similar view showing the charging-carriage 20 coupled to the cover, the latter being dislodged from its closed position and showing the charge falling into the furnace. Fig. 3 is a top plan of Fig. 1 with parts broken away. Fig. 4 is an end view of the apparatus, the 25 rails being in section on line 4 4 of Fig. 3. Fig. 5 is an enlarged detail in side elevation of the carriage-frame, showing ends of the leaves or flights of the conveyer and link belt therefor. Fig. 6 is a transverse section on 30 line 6 6 of Fig. 5. Fig. 7 is an enlarged side elevational detail showing manner of operation of the automatic couplers carried by the water-cooled top or cover, and Fig. 8 is a horizontal section on line 8 8 of Fig. 6.

35 The object of my invention is to provide a charging apparatus for blast or other furnaces, said charger delivering the ore and other material from stock-piles, bins, or bunkers to a point directly over the furnace and 40 feeding the material thereinto, the distribution of the material being under perfect control of the operator as the latter follows the charge during its delivery into the furnace, he being always in position to inspect the condition of the furnace interior, whereby he is 45 enabled to regulate the charge according to said condition.

A further object is to substitute mechanical for manual labor, which, at best, is most trying and arduous.

In detail the apparatus may be described as follows:

Referring to the drawings, F represents the top of a conventional form of blast-furnace, to which lead the track-rails 1 1. The rails 55 communicate with any source of supply for the furnace charge, the material being conveyed to the furnace by a carriage or truck traveling on said rails.

The carriage-frame at its forward end is 60 provided with suitable electric motors M and M', respectively, the former serving to impel the carriage along the rails and the latter to actuate a suitable conveyer, on which the charge has been deposited. This conveyer 65 is composed, preferably, of a series of metal leaves or flights 2, whose terminal deflected ends overlap one another, so as to virtually form a trough for the charge, the several leaves being secured to the link belts or chains 70 3, impelled by the motor M'.

The gearing between the belts and motor may be briefly adverted to, though, of course, it is obvious that any construction of gearing may be used. Leading from the reducing 75 gear case 4 is a shaft 5, carrying a sprocket-pinion 6, which is connected through the link belt 7 to the sprocket-wheel 8. The latter imparts motion to the shaft 9, which carries the sprocket-wheels 10, over which one end 80 of the link belts passes, the opposite ends passing over the rear sprocket-wheels 10', and at intermediate points the lower laps of the belts traveling over idlers 11, which are mounted on a rod 11', carried by the hangers or brackets 85 12. The hangers 12 likewise serve to support the bottom sheet-iron floor or plate 13, which serves to protect the conveyer from the heat of the furnace when the carriage is over the top of said furnace. That the carriage may 90 be driven in either direction the motor M is made reversible, and it may be further added that the motors M and M' may be operated independently. Of course these features I do not claim, as they are not new; but they are 95 mentioned herein to bring out to better advantage the possibilities of the present invention, among these being that the speed of either motor and the direction of the carriage's travel is made instantly variable at the 100

will of the operator. Thus the apron conveyer may be discharging its burden into the furnace at any speed (which speed may be varied at will) while the carriage is being propelled forward and backward or to and fro over the furnace at any desired speed, (this latter being also variable,) or the carriage may be stopped at any point in its travel and the apron or conveyer be caused to discharge its burden or any portion of it while the carriage is stationary.

The floor of the pit of the operator is represented at 14, and it is apparent that his position is such that he can, Fig. 2, inspect the interior of the furnace at all times, and thus be able to impel or move the carriage in any desirable direction and at any desired rate of speed to distribute the charge to the best advantage and as may be required by the furnace's condition. To this feature of variable distribution I attach great importance, since a furnace's condition is often irregular, owing to scaffolding or incrusting and other causes, which conditions are susceptible of remedy by varying the distribution of the charge as such conditions may call for.

A charger of the character described necessarily operates in connection with an open-top furnace, so that the products of combustion—smoke and gases—must be conveyed to the smoke-stack (not shown) by a lateral offtake F', the top being closed by a movable water-cooled top or cover T, which is moved or shoved out of the way by the carriage as the conveyer of the latter dumps its charge into the furnace through the space left open by the dislodgment of the movable top.

The water-cooled top T may be described as follows: It is a flat metal casing or jacket, into which water is admitted through a flexible hose 15, the water circulating around the baffle-plates or diaphragm 16 to insure the best cooling results, finally escaping through an outlet-pipe 17, whence it is conveyed to a discharge-trough 18, carried by the furnace and conducted to any suitable point. Like the carriage, the movable top T travels on the rails 1 1, being suspended from the axles 19, which carry the terminal wheels 20. The end of the top T adjacent to the carriage is provided with bumpers 21 to prevent an overrun of the charger (the term "charger" herein having reference more particularly to the carriage and its conveyer) in effecting a coupling with the top, as presently to be seen. Since the furnace-mouth remains closed by the water-cooled top or cover T at all times, it becomes necessary to move this cover aside during the charging operation, this advance of the cover being effected by the traveling charger as the latter passes over the rails 1 1.

The manner of automatically coupling the charger to and uncoupling the same from the water-cooled top or cover is as follows: Pivoted on either side of the top are the bent

coupling-levers 22, the outwardly-deflected medial portions terminating in the downwardly-inclined extensions 22', extending along the outside of the furnace, and the terminals of the inner parallel portions of the levers being provided with notches 23, which are adapted to engage the lower edge of the angle-bar 24 at the bottom of the anterior portion of the carriage, the ends of the levers being beveled to facilitate the engagement between the parts. Of course the levers are pivoted to one side of their center of gravity, said center being on the side of the portions 22', whereby the notched ends will tend to swing upward and force themselves into positive engagement with the member 24, aforesaid. For the coupled position of the carriage, Fig. 2, the floor 14 of the operator's pit is directly over the adjacent end of the water-cooled top, so that the operator as well as the motors M M' are protected from the heat and gases of the furnace, and when the top T has been shoved wholly from over the furnace the conveyer-flights and link belts are protected from these same gases and heat by the plate or floor 13 of the carriage above referred to. The carriage automatically disengages itself from the couplers by the time the top T has been closed fully over the furnace through the instrumentality of the tripping-pins 25, projecting from the walls of the furnace, said pins striking and raising the inclined ends 22' of the coupling-levers and obviously depressing the opposite notched ends sufficiently to cause the notches to release their hold on the angle-bar 24, as fully apparent from the illustration in Fig. 7, the dotted lines showing the coupled position of the parts. Of course the pins 25 are so located that the disengagement takes place only when the furnace-top is completely covered by the water-cooled top T.

By examining Fig. 2 it must be apparent that all the advantages and possibilities as outlined above are inherent in the present charger. The furnace-top is always closed either by the cover T or by the floor of the carriage, or both, and during the charging operation the only opening left over the furnace is the comparatively narrow passage or chute between the discharging-flights 2 and the posterior wall of the operator's pit. This passage may be likened to a wide-mouthed hose-nozzle waved to and fro across the top of the furnace, the backward and forward motion of the carriage providing this waving motion. The charge escaping through this passage may be likened to a sheet of material deposited across the mouth of the furnace, the distribution being effected so as to produce a uniform product and insure uniformity in the operation of the furnace. Through this chute or passage the operator can inspect the furnace contents as the carriage travels over the mouth of the furnace, whereby he can judge

accurately as to the amount of charge he should feed over any particular spot or any particular area in the furnace.

It is to be understood, of course, that I do not wish to limit myself to the details of construction here shown, as these may be departed from in a measure without affecting the nature or spirit of my invention.

Having described my invention, what I claim is—

1. In a furnace-charger, the combination with a furnace having a charging-opening, of a movable cover normally closing said opening, a traveling conveyer adapted to dislodge the cover and discharge its contents into said opening, and means for moving the conveyer along the opening to distribute the charge, substantially as set forth.

2. In a furnace-charger, a suitable traveling carriage adapted to be impelled to and from the furnace, a conveyer mounted on the carriage for delivering the charge to the furnace, said conveyer being adapted to be impelled independently of the carriage, a traveling furnace top or cover adapted to normally close over the charging-opening of the furnace, the cover being adapted to be moved by the carriage in its reciprocations, thereby uncovering the charging-opening for admitting the material into the furnace, substantially as set forth.

3. In a furnace-charger, the combination with a furnace having a charging-opening, of a movable top or cover normally closing said opening, a traveling conveyer adapted to dislodge said cover for purposes of discharging into the furnace, means for coupling the cover to the conveyer upon such dislodgment, the conveyer being adapted to move or reciprocate along the opening to distribute the charge, and draw the cover with it in such movements or reciprocations, substantially as set forth.

4. In a furnace-charger, a suitable traveling carriage adapted to be impelled to and from the furnace, a conveyer mounted on the carriage for feeding the charge to the furnace, a traveling top or cover normally closing the charging-opening of the furnace, the advancing or anterior end of the carriage-floor being adapted to partially overlap the cover, means on the cover for limiting the advance of the carriage in the direction of the cover, means for coupling the carriage to the cover for the overlapping position of the former, a protecting floor or plate for the carriage, the carriage and cover being adapted to travel together over the charging-opening of the furnace, a suitable space being left between the delivery end of the conveyer and the operator's pit for the discharge of the material into the furnace, substantially as set forth.

5. In a furnace-charger, a suitable traveling carriage operating in connection with the furnace, a conveyer mounted on the carriage and

having independent driving mechanism, a water-cooled traveling top or furnace cover adapted to be coupled to, and propelled by said carriage, and coupling devices mounted on the cover for engaging the carriage, substantially as set forth.

6. In a furnace-charger, a suitable traveling top or furnace-cover, bent coupling-levers pivoted on either side of the cover and having depending downwardly-inclined terminals overhanging the vertical walls of the furnace, notches formed at the opposite ends of the levers for effecting engagement with a suitable charger, and pins projecting from the walls of the furnace for engaging the inclined terminals and thus releasing the coupling-levers from the charger in the movement of the latter from the furnace, substantially as set forth.

7. In a furnace-charger, the combination with a furnace having a charging-opening, of a movable cover normally closing said opening, a traveling carriage operating in connection with said opening, a conveyer mounted on the carriage and having independent driving mechanism, and means for coupling said cover to the carriage whereby the two travel in unison during the movements of the carriage, substantially as set forth.

8. In combination with a furnace having a traveling or movable cover normally closing its charging-opening, a charging-carriage adapted to dislodge the cover from its closed position and deposit its material in sheets across the opening into the furnace, substantially as set forth.

9. In combination with a furnace, a suitable charger adapted to travel to and fro over the top of the furnace, and means for permitting the deposit of the material into the furnace during the travel of said charger over the opening of said furnace, substantially as set forth.

10. The combination with a furnace having a charging-opening, of a movable cover normally closing said opening, a traveling charger adapted to dislodge the cover, said charger having a feed-chute adapted to discharge the material through the uncovered section of the opening left by the dislodgment of the cover, the balance of such uncovered section being closed by the passage of the charger thereover, substantially as set forth.

11. The combination with a furnace having a charging-opening, of a cover normally closing said opening, and a charger adapted to dislodge said cover and simultaneously close the opening in proportion as the same is left uncovered by such dislodgment, substantially as set forth.

In testimony whereof I affix my signature in presence of two witnesses.

WILLIAM HUGH FREELAND.
